DESIGN FOR A HANDLE ANCHORING LOOP FOR LUGGAGE AND LIKE CASES

Abraham Levine, Elizabeth, N. J.

Application March 27, 1940, Serial No. 91,277

Term of patent 14 years

To all whom it may concern:

Be it known that I, Abraham Levine, a citizen of the United States, residing at Elizabeth, county of Union, and State of New Jersey, have invented a new, original, and ornamental Design for a Handle Anchoring Loop for Luggage and Like Cases, of which the following is a specification, reference being had to the accompanying drawing, forming part thereof.

In said drawing, Fig. 1 is a top plan view, Fig. 2 is a side elevational view, and Fig. 3 is an end elevational view of a handle anchoring loop for luggage and like cases, showing my new design.

I claim:

The ornamental design for a handle anchoring loop for luggage and like cases, as shown.

ABRAHAM LEVINE.
